UNITED STATES PATENT OFFICE.

HERMANN BUSCHER, OF LANGERFELD, NEAR BARMEN, GERMANY, ASSIGNOR TO MAX HENKELS, OF NEW YORK, N. Y.

LACE-BRAIDING MACHINE.

Application filed January 2, 1923. Serial No. 610,472.

To all whom it may concern:

Be it known that I, HERMANN BUSCHER, a citizen of the German Empire, residing at Langerfeld, near Barmen, Germany, have 5 invented certain new and useful Improvements in Lace-Braiding Machines, of which the following is a specification.

My invention relates to a lace-braiding machine in which the bobbin-carriers can be 10 arrested by being withdrawn from the constantly rotated drivers and locked in enlargements of the bobbin-track, said enlargements being usually formed at the crossings of the bobbin-track by partly removing certain points of the track-plate. It specially 15 refers to a braiding machine of the type described and claimed in my prior Patent No. 1,034,688 in which a pattern gear controlled rod is arranged, said rod being movable up 20 and down and projecting above the track plate. Below the track plate a so-called bobbin-withdrawer is mounted on the rod consisting of a guide-member adapted, when the rod is lifted, to guide a bobbin-carrier 25 into an enlargement of the bobbin-track and to lock it there, whereas to the upper end of said rod a pawl-like member is linked which, on the descent of the rod moves out laterally and presses against the upper guide- 30 disc of the bobbin-carrier, thus pushing the latter back into the bobbin-track within the reach of the drivers.

In this known machine the guide of bobbin-carriers which are intended to pass the 35 crossings of the bobbin-track without being arrested is a somewhat defective one because of the missing points of the track-plate. The object of my present improvements is therefore to more perfectly guide those bobbin-carriers by so constructing the aforesaid pawl-like member that it performs the office 40 of the missing track-plate point when the pattern gear controlled rod to which said member and also the aforesaid bobbin-withdrawer are attached is lowered. According 45 to my invention a substantially triangular plate is arranged on the upper side of the free end of the pawl-like member, said plate being adapted to co-act with the stem of a 50 bobbin-carrier and thus to guide the latter securely past the enlargement of the bobbin-track. Other features of my invention appear from the following description setting forth more fully my improvements with reference to the annexed drawings, in which—

Figs. 1 and 3 are plan views of a part of a lace-braiding machine of the type referred to,

Fig. 2 is a sectional elevation on the line 2—2 of Fig. 1, and

Fig. 4 is a sectional elevation on the line 4—4 of Fig. 3.

The plates *b*, *b* are as well known in the art laid out in a circle. They are positioned in recesses of the track-plate *a*, which forms the outer curvature of the bobbin-track. The latter is, as clearly shown in Figs. 1 and 3, composed of two undulatory tracks crossing each other between two adjacent plates *b*, *b*. Below the plates *b*, *b* the drivers *c*, *c* are arranged, which, being continuously rotated, the one to the left, the other to the right, impart motion to the bobbin-carriers *g* first in the one direction and then in the other depending on the particular driver by which a bobbin-carrier is driven. Alternately on the inner side and outer side of the bobbin-track there are provided at the crossings of the latter tongue-switches *q*, which serve, in a well-known manner for directing the bobbin-carriers according to the braid to be produced. Opposite each tongue-switch *q* the track-plate points normally projecting in between two adjacent plates *b*, *b* is terminated so as to form an enlargement of the bobbin-track in which a bobbin-carrier may be arrested. Below each blunt track-plate point a so called bobbin-withdrawer *d* is provided. The latter possesses at its end facing the bobbin-track a guide rail *f*, which, when the withdrawer is in its lifted position, engages the downwardly projecting pin *g*¹ of a bobbin carrier and leads the latter into the enlargement of the bobbin-track. In this way the bobbin-carrier is withdrawn from the drivers and arrested (see right-hand part of Fig. 1 and left-hand part of Fig. 2).

Each bobbin-withdrawer *d* is mounted on a vertical rod *i* guided in co-axial borings of the lower plate *h* and of the track-plate *a*. A coiled spring *k* surrounding the rod *i* tends to hold said rod in its uppermost position in which an abutment-ring *m* fastened to the rod bears against the underside of plate *h*. With the lower end of the rod *i* a tie-rod of the pattern gear (not shown) is connected so that the rod, in a well known manner, may be pulled down by means of the pattern-gear. The upper end of the rod *i*

which projects above the track-plate *a* has an arm *n* attached to it, to which is pivoted a pawl-like member *o*, resting with its free end *o*¹ on the track-plate *a* just behind the upper guide-disc *g*² of a bobbin-carrier arrested at the corresponding track-plate point. On the descent of the rod *i* said pawl-like member *o* moves out laterally and, pressing against the guide disc *g*², pushes the arrested bobbin-carrier back into the track within the reach of the drivers *c*, *c*. See left-hand part of Fig. 1 and right-hand part of Fig. 3.

According to my invention a substantially triangular plate *r* is arranged on the upper side of the free end *o*¹ of the pawl-like member *o*, said plate *r* being so shaped that it performs the office of the missing track-plate point when the rod *i* is lowered and the pawl-like member *o* moved out laterally (see Figs. 3 and 4). It may thereby, as shown, be fastened to the pawl *o* by screws or the like or form an integral part of said pawl. The plate *r*, being adapted to co-act with the stem *g*³ of a bobbin-carrier, serves to guide those bobbin-carriers which are intended to pass the crossings of the bobbin-track without being arrested. To this end the rod *i* with the bobbin-withdrawer *d* is lowered before the downwardly projecting pin *g*¹ of a bobbin-carrier can engage the guide-rail *f* of the withdrawer *d*. Thus, on the one hand, the arresting of the bobbin-carrier approaching the crossing of the bobbin-track is avoided, while on the other hand, the bobbin-carrier is by means of the triangular plate *r* securely guided past the enlargement of the bobbin-track. In order that the upper guide-disc *g*² of the bobbin-carrier may not run against the pawl-like member *o*, the free end of the latter is, on its underside, provided with two outwardly and upwardly inclined faces *p*¹, *p*² so that the pawl *o* may be lifted by the guide disc *g*² of the bobbin-carrier while said guide disc slides underneath the pawl *o*. By this means I am not only enabled to provide for a sufficiently broad working face at the free end *o*¹ of the pawl *o*, but I may, at the same time, somewhat shorten the triangular plate *r* so that, on pushing an arrested bobbin-carrier again into the path of the drivers the point of said plate *r* does not contact the stem *g*³ of the bobbin-carrier. Consequently the restoring of an arrested bobbin-carrier to the track is effected by the broadened free end *o*¹ of the pawl *o* only, thus avoiding undue wear of the point of the plate *r*. On guiding those bobbins intended to pass the crossing of the bobbin-track without being arrested, the shortening of the plate *r* is compensated by the lifting of the free end of the pawl *o* which causes a somewhat larger lateral movement of the latter.

65 I wish to state that my invention is not

restricted to the exact construction as shown on the drawings for many alterations or variations may suggest themselves to those skilled in the art without departing from the spirit of my invention as pointed out in 70 the claims.

Claims:

1. A lace-braiding machine comprising: a bobbin-track and bobbin-carriers guided therein, said bobbin-track having enlargements for temporarily arresting bobbin-carriers, constantly rotating drivers for said bobbin-carriers, a pattern-gear controlled rod movable up and down, a guide-member mounted on said rod for guiding a bobbin-carrier into an enlargement of said bobbin-track and out of the path of said drivers, a pawl-like member linked to the upper end of said rod for restoring an arrested bobbin-carrier to the path of the said drivers, a substantially triangular plate on the free end of said pawl-like member for guiding a non-arrested bobbin-carrier past the enlargement of said bobbin-track. 75 80 85

2. A lace-braiding machine comprising: a bobbin-track and bobbin-carriers with guide discs guided in said track, said bobbin-track having enlargements for temporarily arresting bobbin-carriers, constantly rotating drivers for said bobbin-carriers, a pattern-gear controlled rod movable up and down, a guide-member mounted on said rod for guiding a bobbin-carrier into an enlargement of said bobbin-track and out of the path of said drivers, said guide-member being adapted to co-act with downwardly projecting pins of said bobbin-carriers, a pawl linked to the upper end of said rod for restoring an arrested bobbin-carrier to the path of said drivers, 95 100 105 the free end of said pawl being guided in the plane of the upper guide discs of said bobbin-carriers and adapted to co-act with said guide-discs, a substantially triangular plate provided on the upper side of the free 110 end of said pawl for guiding a non-arrested bobbin-carrier past the enlargement of said bobbin-track, said triangular plate being adapted to co-act with the stems of said bobbin-carriers. 115

3. A lace-braiding machine comprising: a bobbin-track and bobbin-carriers with guide discs guided in said track, said bobbin-track having enlargements for temporarily arresting bobbin-carriers, constantly rotating drivers for said bobbin-carriers, a pattern-gear controlled rod movable up and down, a guide-member mounted on said rod for guiding a bobbin-carrier into an enlargement of said bobbin-track and out of the path of said drivers, said guide-member being adapted to co-act with downwardly projecting pins of said bobbin-carriers, a pawl linked to the upper end of said rod for restoring an arrested bobbin-carrier to the 120 125 130

- path of said drivers, the free end of said pawl being normally guided in the plane of the upper guide discs of said bobbin-carriers and adapted to co-act with said discs,
5 a substantially triangular plate provided on the upper side of the free end of said pawl for guiding a non-arrested bobbin-carrier past the enlargement of said bobbin-track, said plate being adapted to co-act
10 with the stems of said bobbin-carriers, and outwardly and upwardly inclined faces on the underside of the free end of said pawl for temporarily lifting said pawl above the upper guide-disc of a non-arrested bobbin-carrier, said faces being adapted to co-act 15 with said upper guide-disc.

In testimony whereof I affix my signature in presence of two witnesses.

HERMANN BUSCHER.
